FRED W. PULLEN AND FRED W. HALL, OF GRAND RAPIDS, MICHIGAN, ASSIGNEES TO
BISSELL CARPET SWEEPER COMPANY, OF GRAND RAPIDS, MICHIGAN

TOY CARPET SWEEPER

Application filed December 21, 1928. Serial No. 327,530.

The main objects of this invention are:

First, to provide an improved toy sweeper whereby the cost of manufacture is greatly reduced.

Second, to provide improved driving parts and assembly for same.

Objects pertaining to details and economies of the invention will definitely appear from the description to follow. The invention is defined in the claims.

10 A structure which embodies the features of our invention is clearly illustrated in the accompanying drawings, in which:

Fig. 1 is a side perspective view of my improved toy sweeper, part of the handle being broken away.

Fig. 2 is a longitudinal sectional taken on line 2—2 of Figs. 1 and 3, a portion of the brush being shown by dotted lines.

20 Fig. 3 is a vertical section taken on line 3—3 of Fig. 2, showing the dust pans and the tension spring for holding them yieldingly in contact with the case.

Fig. 4 is an enlarged sectional view taken 25 on line 4—4 of Figs. 1 and 3 showing mainly the pivotal means for the dust pan which is the floor wheel axle.

The parts will be identified by their numerals of reference. 1 is the main body or 30 case of our improved sweeper. 2 are the ends slotted at 21 for the brush spindle. 3 is the brush retained by the twisted wire 31, a usual form. 4 is the brush pulley. 5 are the floor wheels journaled at 51 on a straight 35 round headed nail which is pivoted in the wood end of the case and driven into the end of the dust pan at each end as shown.

The peripheries of the floor wheels are spaced apart a distance less than the brush 40 pulley diameter and support the brush pulleys at each end so that gravity action is insured.

45 6 is the dust pan of wood or similar material shouldered at 61 to engage the bottom of the casing 1 and is pivotally mounted by the pins 51 in the case ends.

50 62 is a straight spring having inwardly turned ends 63 engaging the ends of the dust pans and in perpendicular relation to the pivots, and beneath the said pivots to retain

the pans in closed position so they will open against spring action. The springs, being below the brush spindles, prevent accidental separation.

7 is the usual bail or handle pivoted in the aperture in the ends 2.

As the sweeper is operated the action of gravity on the brush pulleys 4 causes a frictional engagement with the floor wheel, thereby rotating the brush. The slot 21 in the side 55 2 accommodates the brush in its up and down movement. The dust pan 6 is carried by the journal 51 which also serves as axle for the floor wheel 5 in each instance. The springs 60 62 are secured to the ends of the dust pans in a perpendicular relation to the pivots. These springs provide the necessary tension to maintain the closed position of the dust pans.

As the dust pans are opened the axial 70 movement of the spring end tends to shorten the space between the two inturned ends 63, thereby serving to stress the same and to force the lower ends of the dust pans up to closed position as soon as they are released.

75 There are many wood substitutes being produced at the present time, and in claiming our invention we wish to claim particularly wood dust pans. We also wish to claim broadly the said dust pans made of any wood fiber substitute.

Having thus described our invention, what we claim as new and desire to secure by Letters Patent, is:

1. In a carpet sweeper, the combination of 85 a casing with its ends slotted from the bottom for the brush spindle, a rotary brush with its spindle projecting at both ends and disposed in said slots, brush pulleys on the ends of the brush spindle, dust pans of comparatively 90 massive dimensions of wood within the bottom of said case, floor wheels disposed to support and drive the brush pulley, axle pins for the said floor wheels driven into the ends of the said dust pan and pivoting in the frame 95 ends, and a straight spring rod with right angled ends, the said ends being driven into the ends of said dust pans and connecting the said dust pans at points below their pivots to hold the dust pans yieldingly closed and 100

disposed beneath the brush spindle to prevent displacement of said brush.

2. In a carpet sweeper, the combination with a casing and brush, of dust pans pivotally supported at each side of the brush, straight rod springs having their ends connected to said dust pans at points below their pivots to hold the said dust pans in closed position and permit them to be opened against spring pressure.
3. In a carpet sweeper, the combination of a casing with its ends slotted from the bottom for the brush spindle, a rotary brush with its spindle projecting at both ends and disposed in said slots, brush pulleys on the ends of the brush spindle, dust pans of comparatively massive dimensions of fiber material within the bottom of said case, floor wheels disposed to support and drive the brush pulley, axle pins for the said floor wheels driven into the ends of the said dust pans and pivoting in the frame ends, and a straight spring rod with right angled ends, the said ends being driven into the ends of said dust pans and connecting the said dust pans at points below their pivots to hold the dust pans yieldingly closed and disposed beneath the brush spindle to prevent displacement of said brush.

In witness whereof we have hereunto set
30 our hands.

FRED W. PULLEN.
FRED W. HALL.
